DESIGN FOR AN AWNING

Daniel D. Kobbe, Houston, Tex., assignor to
Aluminum Arts, Inc., Houston, Tex., a corpora-
tion of Texas

Application January 3, 1947, Serial No. 135,924

Term of patent 14 years

(Cl. D21—6)

To all whom it may concern:

Be it known that I, Daniel D. Kobbe, a citizen
of the United States, residing at Houston, in the
county of Harris and State of Texas, have in-
vented a new, original, and ornamental Design
for Awning, of which the following is a specifica-
tion, reference being had to the accompanying
drawing, forming part thereof.

Fig. 1 is a front elevational view of an awning,
showing my new design;

Fig. 2 is a perspective view of the awning.

I claim:

The ornamental design for an awning, as shown.

DANIEL D. KOBBE.
